ABSTRACT: A low-temperature liquefied gas storage tank comprising an outer tank made of rigid metals and an inner tank having a thin film construction. The inner tank is provided at its upstanding peripheral inside surface with vertically extending corrugations and includes means for suspending its upper peripheral edge so as to permit contraction and expansion of the inner tank when it is subjected to a liquid load or exposed to a low temperature. The inner tank prevents undesirable cracking and damage thereof and can store the low-temperature liquefied gas in a safe manner.

LOW TEMPERATURE LIQUEFIED GAS STORAGE TANK

This invention relates to tanks for use in storing gases such as methane, ethane, ethylene, propane in liquid state, each of which is gaseous state at room temperature under atmospheric pressure, but can be liquefied by cooling to its boiling point under atmospheric pressure.

Such low-temperature liquefied gas storage tank heretofore proposed comprises a cylindrical inner tank having a flat bottom portion and a spherical cover roof portion, a cylindrical outer tank provided around the inner tank, and granular heat insulating material filled in a space formed between the inner and outer tanks, thereby forming so called a double-walled tank. Such tank heretofore proposed makes use of granular heat insulating material such as perlite as the heat-insulating material so that the heat-insulating layer can be formed in a comparatively easy and less expensive manner, but has disadvantages that both of the inner and outer tanks must be made of metal, that the inner tank must be made of low temperature resistant material and can withstand the inner pressure produced therein, and that the low-temperature liquefied gases could not be stored in a safe manner.

The principal object of the invention is to provide a storage tank without having the above-mentioned disadvantages inherent to the heretofore proposed tanks and a tank that is highly safe in operation.

A feature of the invention is the provision of such an improved storage tank which comprises an inner tank containing low-temperature liquefied gas and having a thin film construction whose peripheral inside surface has specially shaped vertically extending corrugations and means for suspending the upper peripheral edge of the inner tank so as to permit contraction and expansion of the inner tank when it is subjected to a liquid load or exposed to a low temperature and hence prevent cracking and damage of the inner tank owing to contraction phenomenon of the inner tank as a whole, with the result that the low-temperature liquefied gas can be stored in a safe manner.

A liquefied gas storage tank according to the invention comprises, in combination, an outer tank having a pressure-tight and hermetically sealed construction, a heat-insulating layer having substantial resistance to compression provided in the inside surface of at least side and bottom portions of said outer tank, and an inner tank having a thin film construction and provided in the inside of said heat-insulating layer, the pressure of the liquefied gas being supported through said heat-insulating layer by said outer tank, said inner tank having the thin film construction being formed into a bag shaped body consisting of a flat bottom plate and a side shell connected through a thin film connector construction in the form of a portion of a toroid to said bottom plate, the upper peripheral edge of said bag-shaped inner tank being connected through a longitudinally followable device to a top structure of said outer tank, an upper opening of said inner tank being covered by a top cover plate secured to said top structure independently of said inner tank and provided at its top side with a heat-insulating layer, and said inner tank having vertically extending corrugations arranged in spaced relation at the periphery of said side shell and smoothly terminating at the neighborhood of said connector construction.

Additional objects of the invention together with the features contributing thereto and the advantages accruing therefrom will be apparent from the following description when read in conjunction with the drawing, wherein:

FIG. 1 is a vertical sectional view of a storage tank according to the invention;

FIG. 2 is a perspective view of bottom parts of the tank shown in FIG. 1, in which a part is shown in a sectional view;

FIGS. 4-A and 4-B are diagrammatic cross sections through the inner tank shown in FIGS. 1 and 2 for explaining the contraction change thereof;

FIG. 5 is a front view of the outside surface of the inner tank; and

FIGS. 6, 7 and 8 are fragmentary radial cross sections showing different embodiments of devices connecting the upper peripheral edge of the inner tank to the outer tank.

Referring now to FIG. 1 there is shown a sectional view of a storage tank according to the invention having a rigid outer tank 1 having a pressure-tight and hermetically sealed construction and made of steel, designates a heat insulating material having a substantial resistance to compression such, for example, as a heat insulating layer consisting of hard polyurethane etc. Inside of this heat insulating layer 2, an inner tank 3 is provided. This inner tank 3 is constructed by a thin film construction made of a low-temperature resistant material such as aluminum, nickel steel etc. The inner tank 3 has a sufficient flexibility and is constructed such that when it is subjected to the inner pressure it could not withstand such inner pressure and hence is deflected towards and brought into close contact with the heat-insulating layer 2, thereby transmitting the inner pressure to the latter. Therefore, substantially all of the inner pressure is supported by the rigid outer tank 1 having the pressure-tight construction. The inner tank 3 consists of a flat bottom plate 6 and a cylindrical side shell connected through a thin film connector construction 5 in the shape of a portion of a toroid to the bottom plate 6. The cylindrical side shell plate is provided with vertically extending corrugations 4 which permits the cylindrical side shell plate to expand and contract in the peripheral direction thereof. 7 shows a top cover construction of the outer tank 1 and 8 a truss for supporting the top cover plate 7. 9 shows a balancing weight device that suspends the upper peripheral edge of the inner tank 3 and moves downward when the low-temperature liquefied gas is charged in the inner tank 3 to compensate for the contraction of the side shell of the inner tank 3. 10 designates a top cover for the inner tank, which is constructed by a thin plate made of Al, Ni-steel etc. and whose outer peripheral edge in opposition with the inner tank 3 is bent downwards to form a small gap therebetween. 11 illustrates a heat-insulating material which is not required to be of a compression resisting type and is made for example of glass wool etc. 12 designates a member made of wood etc. and adapted to support the top cover 10 of the inner tank 3 and connect the top cover 10 to the truss 8.

Various types of the devices for suspending the upper peripheral edge of the inner tank 3 may be constructed and embodiments thereof will now be explained with reference to FIGS. 6-8.

In the embodiment shown in FIG. 6 the upper peripheral edge 13 of the inner tank 3 is pivoted to one end of a rocking lever 14 arranged on the top cover 10 and pivoted to it. The rocking lever 14 is provided at its opposite end with a weight 15 which is always in balance with that end which suspends the upper peripheral edge 13 of the inner tank 3.

In another embodiment shown in FIG. 7 the upper peripheral edge 13 of the inner tank 3 is suspended through a spring or bellows 16 from the top cover construction 7 of the outer tank 1.

In a further embodiment shown in FIG. 8 the upper peripheral edge 13 of the inner tank 3 is suspended through a wire and a pulley 17 from the top cover construction 7 of the outer tank 1 and always in balance with a weight 18 acting upon the pulley 17. All of these embodiments provide means for freely following the load produced by the low-temperature liquefied gas charged in the inner tank 3 and hence follow the displacement of the upper peripheral edge 13 of the inner tank 3.

The above-mentioned construction according to the invention in which the inner tank 3 is made of the thin film renders it possible to bring the inner tank 3 into a close contact with the heat-insulating layer 3 by means of the inner pressure produced by the low-temperature liquefied gas charged in the inner tank 3 thus transmitting the inner pressure to the heat-insulating layer 2, with the result that the outer tank 1 can withstand the above-mentioned inner pressure and hence can store the low-temperature liquefied gas in a safe manner. How

to compensate for the deflection of the inner tank 3 caused by the abovesmentioned inner pressure and the contraction of the inner tank 3 caused by the low-temperature liquefied gas will now be described.

As shown in FIG. 2, the bottom plate 6 when exposed to the low temperature becomes contracted towards the center thereof so that a demarcation line *cd* located at room temperature between the connector construction 5 and the bottom plate 6 of the inner tank 3 is displaced to dotted lines *c'd'* and hence a demarcation line *ab* located at room temperature between the side shell 3 and the connector construction 5 is displaced to dotted lines *a'b'*, thus moving the side shell 3 downwards. Such downward movement of the side shell 3 is capable of compensating for the contraction of the bottom plate 6. FIG. 3 diagrammatically illustrates the contraction of the inner tank 3 shown in vertical cross section. As seen from FIG. 3 the inner tank 3 takes a sectional form shown by a full line *a—c* at room temperature under no load condition. The bottom plate 6 when exposed at the low temperature under the no load condition is contracted towards its center to displace a point *c* to a point *c'*. The contraction of the side shell reduces the diameter of the inner tank 3 and hence displaces a point *a* to a point *a'*, with the result that a full line *a—c* is displaced to dotted lines *a'—c'*. The liquid load applied to the inner tank 3 having the thin film structure tends to the inner tank 3 to deflect and bring it into a close contact with the heat-insulating layer 2, thereby tending to displace the dotted lines *a'—c'* to the original full line *a—c*. In this case the contraction of the bottom plate 6 from the point *c* to the point *c'* and the contraction of the side shell plate 3 from the point *a* to the point *a'* tend to bring back the point *a'* to the point *b* instead of bringing back the point *a'* to the point *b* instead of bringing back the point *a'* to the point *a*. As seen from the above description the deflection of the inner tank 3 caused by the liquid load at the low temperature consists of a longitudinal contractive displacement represented by the movement of the point *a* to the point *b*, a peripheral expansion of the side shell 3 from the dotted lines *a'—c'* under no load condition to the full line *b—c* under loaded condition, and a change of curvature of the connector construction 5. The longitudinal contractive displacement can freely be carried out with the aid of the balancing weight device 9 suspending the upper peripheral edge 13 of the inner tank 3, while the peripheral expansion of the side shell plate can be carried out by deformation of the longitudinal corrugations 4. Such deformation of the corrugations 4 is illustrated in FIG. 4-A in which a full line shows the state of the shell 3 in section at room temperature under no load condition and dotted lines show how the side shell 3 deforms at the low temperature under load condition. The corrugations 4 become expanded by the presence of the inner pressure.

As seen from FIG. 4-A points *d*, *e* and *f* are displaced to points *d'*, *e'* and *f'*, respectively, and the distance between the points *e* and *f* is reduced by contraction to that between the points *e'* and *f'*. The deformation of the corrugations 4 causes the distance between the points *d* and *e* to increase to that between the points *d'* and *e'*. Thus, the elongation between the points *d* and *e* compensates for the contraction between the points *e* and *f* thus bringing the side shell plate 3 into contact with the heat insulating wall 2. The corrugations 4 are liable to be easily deformed by an extremely small force so that dangerous thermal stress is not produced in the side shell 3. FIG. 4-B shows a variant of the corrugations 4 shown in FIG. 4-A in which corrugations 4 are different in shape from the corrugations 4 shown in FIG. 4-A. In the present embodiment the corrugations 4 constitute a camber of a plate. This camber is eliminated by contraction of the side shell 3 at the low temperature to deform the side shell 3 into a circular form without undulations in section, thereby bringing it into a close contact with the inside surface of the heat-insulating layer 2. Thus, the corrugations herein described also means the above mentioned camber.

The inner tank 3 is constructed by a thin film and the corrugations terminate smoothly at the neighborhood of the connector construction 5 so that the curvature of the connector construction 5 can be changed without difficulty. Such change of the curvature of the connector construction 5 may more easily be carried out by provision of additional corrugations (not shown) along the periphery of the connector construction 5. Thus, the inner tank according to the invention can be easily deformed in response to the load and the contraction phenomenon due to the low temperature and thereby reduces crack and damages of the tank and stores the low-temperature liquefied gases in a safe manner.

The downwards bent peripheral edge of the top cover 10 of the inner tank 3 prevents the low-temperature liquefied gas from flowing out of the inner tank 3 even when the level of the low-temperature liquefied gas abruptly changes owing to earthquake or other causes. The small gap formed between the downwards bent peripheral edge of the top cover 10 and the upper peripheral edge 13 of the inner tank 3 serves to allow communication between inside and outside of the inner tank 3 and hence passage of vapor.

That part of the vapor which makes contact with the inside surface of the outer tank 1 which is commonly made of steel plate, is heated to ambient temperature so that the outer tank is not liable to be brittle and hence damaged owing to the low temperature.

The space formed between the inner and outer tanks is filled with vapor so that frost and ice etc. do not occur at those portions which are positioned in this space without necessitating any means of drying the space formed between the inner and outer tanks, as in double-walled tanks heretofore proposed.

It will be seen that the storage tanks according to the invention are simple and economical to construct, and result in a considerable safety in the storage of the low-temperature liquefied gases.

It is to be understood that the forms of the invention herewith shown and described are to be as preferred examples of the same, and that various changes in the shape, size and arrangement of the parts may be resorted to without departing from the spirit of the invention or the scope of the subjoined claims.

We claim:

1. A liquefied gas storage tank comprising, in combination, an outer tank having a pressure tight and hermetically sealed rigid construction, a heat-insulating layer having a substantial resistance to compression and provided at the inside surface of at least side and bottom portions of said outer tank, a top closure structure provided on said outer tank, an inner tank having a thin wall construction located inwardly of said heat insulating layer and adapted to contain a low-temperature liquefied gas therein, the pressure of said liquefied gas being supported through said inner tank and heat insulating layer by said outer tank, said inner tank being formed into a bag-shaped body consisting of a flat bottom plate and a cylindrical side shell connected at its bottom edge to said flat bottom plate by a thin film connector construction in the shape of a portion of a toroid. Said side shell including an upper, peripheral edge defining an upper opening, movable suspension means connecting said upper peripheral edge of said bag-shaped inner tank to said top closure structure of said outer tank, said upper opening of said inner tank being covered by a top cover plate secured to said top closure structure independently of said inner tank and provided with a heat-insulating layer, and said inner tank having elongated substantially vertical corrugations arranged in spaced relationship about the periphery of said side shell, said corrugations extending radially across said connector construction and smoothly reducing in width as they approach said flat bottom plate and smoothly terminating in the area of the junction of said connector constructions to said flat bottom plate.

2. A liquefied gas storage tank as claimed in claim 1 wherein said suspension means comprises a plurality of rocking levers

3,570,700

5

pivotably connected to said top cover plate, weight means at one end of each of said levers to counterbalance said inner tank, and said upper periphery of said inner tank being connected to the other ends of said levers.

3. A liquefied gas storage tank as claimed in claim 1 wherein said suspension means comprises a plurality of spring means connecting said upper periphery of said inner tank to said top structure.

4. A liquefied gas storage tank as claimed in claim 1 wherein said suspension means comprises a plurality of pulleys at

6

tached to said top structure and weight means, each of said weight means being attached to a line, and each line passing over at least one pulley and connecting to said upper periphery of said inner tank.

5. A liquefied gas storage tank as claimed in claim 1 wherein said corrugations are constituted by a slightly curved camber adapted to be deformed into substantially a circular form in horizontal section upon being subjected to a low-temperature liquid load.
